J. DOUGLASS

HEADER FOR OIL TANKS

Filed Feb. 27, 1924

UNITED STATES PATENT OFFICE.

JOSEPH DOUGLASS, OF OKMULGEE, OKLAHOMA.

HEADER FOR OIL TANKS.

Application filed February 27, 1924. Serial No. 695,519.

This invention relates to a method and apparatus for handling oil.

In accordance with present practice the production of a number of pumping or flowing wells on a lease is introduced into a common tank or other container and the more or less violent contact of the oil from the several flow lines lowers the gravity and consequently the market value of the oil.

It is, therefore, an important object of the invention to provide a header for oil tanks having means whereby violent contact of the production from the several wells is avoided so that the gravity of the oil is not unnecessarily lowered.

Another object of the invention is the provision of a method of coordinating a plurality of streams of oil into a single stream in a manner to prevent variations in the gravity of the oil when introduced simultaneously into a tank.

A further object is to provide a header wherein simple means is provided to take samples of and to observe the production from the several wells so that it is not necessary to go to each well for the purpose of taking samples and making observations.

A further object is to provide a header having means whereby the gas which collects in the header may be carried off to be used for fuel or the manufacture of gasoline.

A further object is to provide a header which may be conveniently attached to an oil tank, or the like, and which will be favorably received in the industry because of the fact that it may be installed without the abandonment of present expensive equipment and without the exercise of unusual skill.

Other objects and advantages will be apparent during the course of the following description.

In the accompanying drawing forming a part of this application and in which like numerals are employed to designate like parts throughout the same,

Figure 1 is a perspective of the improved header applied;

Fig. 2 is a vertical sectional view through the header applied, and

Fig. 3 is a vertical sectional view through a modified form of the invention applied.

Figure 4 is a horizontal section taken along the line 4—4 of Figure 3.

In the drawing, the numeral 5 designates a tank of iron, wood, or other suitable material, the top wall or the roof 6 of which is provided with an opening for the reception of the oil from the header 7.

The improved header is preferably in the nature of a cylindrical body 8, the lower portion of which is funnel shaped as indicated at 9 so that the several streams of oil will be gradually merged into one for entrance into the tank.

The top wall of the header is provided with a plurality of threaded openings 10 for the reception of attaching nipples or nozzles 11 of flow lines 12. The several flow lines 12 extend from different wells on the lease and convey the oil and a limited quantity of gas from the wells to the tank by way of the receiver or header 8.

It will be seen with reference to Fig. 2 that the oil from the several flow lines enters the receiver in substantially parallel streams and these streams contact with the funnel shaped bottom and are thereby gradually merged into one so that the gravity of the oil is not lowered. In other words, the funnel-shaped portion 9 provides a baffling means spaced from the nozzles 11 to receive and merge the oil into a single stream with variation in the gravity of the oil.

It might be stated at this point that the violent contact of the oil from the several flow lines greatly cuts the oil and consequently lowers the market value of the same. This invention overcomes this disadvantage and, therefore, enables the producer to obtain a higher price for the oil.

Also, the production of the several wells may be accurately observed and separate samples may be taken at the header by the removal of a cap 14 threaded into the top of the header as shown in Fig. 2. The cap 14 may be provided with suitable means to facilitate turning by hand or otherwise. By removing the cap 14 it may be readily ascertained exactly which wells are producing and which wells are not. Also, samples of the production from the different wells may be readily taken for test purposes.

As shown in Fig. 2 one or more gas lines

16 extend from the top wall of the header and conduct the gas which collects in the header to a suitable point of use.

In carrying out the invention, the lower 5 portion of the funnel shaped bottom 9 may be provided with an attaching flange 18 which may be secured to the top wall 6 of the tank by rivets or other suitable fastening devices 19.

10 In the modified form of the invention illustrated in Fig. 3, the header is designated by the numeral 20 and is provided at the upper portion of the funnel shaped bottom 21 with an annular attaching flange 22 se- 15 cured to the top of the tank by fastening devices 23 of any suitable nature.

In this form of the invention the principal flow lines 25 may extend radially into the upper portion of the header to discharge the 20 production from the several wells into separate chambers 50 arranged in the path of travel of the oil and adapted to gradually change the course of the oil. More specifically, the several separate chambers 50 are 25 formed from a plurality of lengths of metal curved longitudinally and secured at their ends to the header at opposite sides of the inlet pipes 25. Figure 3 illustrates that the chambers 50 are provided with curved top 30 walls which cause the oil to gradually change its direction of travel and flow down into the funnel shaped portion 21. Briefly, the several chambers 50 define a baffle by means of which the several lines of fluid are 35 prevented from coming violently into contact with each other.

The top wall of the header 20 may be provided with emergency or supplemental flow lines 28 and with a gas line 29. The header 40 20 is provided with a centrally arranged opening at the top for the reception of an attaching portion of a cap or closure 30.

If desired suitable means such as a pipe 49 may be provided to conduct the production 45 to any depth in the tank before being released.

The principal feature of the method and apparatus forming the subject of this application resides in the fact that the several 50 streams of oil from the wells are gradually merged to avoid lowering of the gravity of the oil and, of course, various sizes of headers, pipes, and observation openings may be employed without departing from the invention.

In fact the foregoing description and the accompanying drawing illustrate that the invention forming the subject matter of this application is capable of a wide variation of 60 mechanical expressions and, therefore, it is to be understood that the form of the invention herewith shown and described is to be taken as a preferred example of the same and that such minor changes in arrangement

and construction of the parts may be made 65 as will remain within the spirit of the invention and the scope of what is claimed.

Having thus described the invention, what is claimed is:

1. A header for oil tanks comprising a 70 receiver having means whereby a plurality of flow lines from different wells may be connected thereto, said receiver being provided with means to gradually merge the several streams of oil entering the receiver 75 whereby to avoid lowering the gravity of the oil.

2. A header for oil tanks comprising a body having a funnel shaped bottom and having means whereby separate flow lines 80 from different wells may be connected thereto, said funnel shaped bottom being in the path of the oil and constituting a means to gradually merge the several streams of oil introduced into the body.

3. A structure of the character specified comprising a receiver, a plurality of inlet members connected to the receiver and disposed substantially parallel to the axis of the receiver, said inlet members being adapted to convey oil from different sources to the receiver, said receiver being provided with a funnel-shaped bottom in the path of travel of the oil from said inlet members whereby to gradually merge the oil from the different inlet members into a single stream and to maintain the gravity of the oil.

4. A header for oil tanks comprising a receiver, a plurality of supply members extending radially into the receiver, and a baffle arranged inwardly of said supply members and adapted to avoid conflicting of the several streams of oil from the supply members.

5. The construction set forth in claim 4, and additional supply members connected to the upper portion of the receiver and extending longitudinally thereof to direct the oil in parallel streams into the receiver.

6. The construction set forth in claim 4, 110 said receiver being provided with a funnel shaped portion to merge the oil from the several supply members.

7. A header for oil tanks comprising a body having means whereby a plurality of radially arranged flow lines may be connected thereto, and a baffle arranged within the header and having a chamber in the path of travel of each stream of oil.

8. The construction set forth in claim 7, 115 the inner wall of each chamber being curved to change the direction of travel of the oil.

9. An apparatus of the class described comprising a plurality of pipes each being adapted to be charged with a supply of oil from a separate source and having discharge nozzles, and means to receive the streams of oil from the nozzles and merge said streams

into a single stream without substantially affecting the gravity of the oil.

10. An apparatus of the class described comprising a plurality of pipes each being adapted to be charged with a supply of oil from a separate source and having discharge nozzles, and means spaced from said nozzles

to receive the streams of oil from the nozzles and merge said streams into a single stream without substantially affecting the gravity of the oil. 10

In testimony whereof I affix my signature.

JOSEPH DOUGLASS.
